UNITED STATES PATENT OFFICE.

OLIVER B. GRAHAM, OF CLEVELAND, OHIO, ASSIGNOR TO AUTO-ORDNANCE CORPORATION, OF NEW YORK, N. Y., A CORPORATION OF NEW YORK.

GUN LUBRICATION.

1,351,164.

Specification of Letters Patent. Patented Aug. 31, 1920.

Application filed July 2, 1919. Serial No. 308,222.

To all whom it may concern:

Be it known that I, OLIVER B. GRAHAM, a citizen of the United States, and resident of Cleveland, Ohio, in the county of Cuyahoga and State of Ohio, have invented new and useful Improvements in Gun Lubrication, of which the following is a specification.

This invention relates to guns and more particularly to automatic firearms, either semi-automatic or full automatic, the objects of the invention being to reduce the friction on the various sliding or rubbing parts of guns, thereby reducing wear on the parts and increasing the speed of operation, to render the operation of the working parts of guns entirely uniform and reliable, to maintain constant the forces of the breech pressure acting on the breech locking mechanism in the case of automatic guns of the type which are unlocked directly in response to the breech pressure, to prevent the heads from being pulled or blown off of cartridges in the firing chambers, to render the extraction of cartridges free and uniform, to increase the velocity of the projectiles, to reduce the wear and heating of the barrel, and generally to improve the operation of guns, particularly automatic guns.

The invention consists in lubricating the contacting surfaces between the firing chamber and the cartridge cases so that the empty cases will not stick in the chamber after firing but will slide out freely and uniformly, lubrication of the cartridge cases being especially important in automatic guns where the uniformity of operation of the breech closing mechanism depends largely upon the free and uniform extraction of the cartridge cases and where the extraction may take place while the residual gas pressure tending to expand the cartridge case against the wall of the firing chamber is still high. The invention also consists in lubricating the sliding surfaces between the various parts of the breech action and between the breech action and the receiver, this also being particularly desirable in automatic guns where excessive or variable friction in the breech action renders the operation erratic and unreliable. Further the invention consists in lubricating the contacting surfaces between the projectiles and the bore of the barrel, this being especially important in automatic guns where

the projectiles are fired at a rapid rate and where it is desirable to maintain the friction between the projectiles and the bore uniform in order to maintain uniform the breech pressure reacting on the breech closure.

The invention also consists in effecting the aforesaid lubrications by a single means by locating the lubricating means in a novel position on the gun and by timing its action in a unique manner with the cyclic operation of the gun. I have found that lubricant may be supplied to the firing chamber of a gun, either before each cartridge is inserted thereinto or from time to time at suitable intervals, in such manner as not only to lubricate the contacting surfaces between the cartridge cases and the firing chamber but also to lubricate the sliding surfaces of the breech action and the contacting surfaces between the projectiles and the bore of the gun. This is preferably effected by ejecting lubricant into the firing chamber, either in the form of a spray or otherwise, immediately in advance of each cartridge so that lubricant will be distributed over both the projectile and the case of each cartridge as it enters the firing chamber. The lubricant deposited on the projectile lubricates the contacting surfaces between the projectile and the bore of the barrel as the projectile shoots through the barrel. The lubricant is preferably transmitted from the firing chamber back to the breech action by so timing the extraction of the empty cartridge cases that a small amount of the residual gas pressure will flow from the mouth of the firing chamber as the empty cartridge case is extracted, thereby carrying lubricant from the firing chamber and depositing same on the breech action. The spray of lubricant into the firing chamber may be so timed with respect to the flow of gas from the mouth of the firing chamber that a part of the lubricant will be carried back to the breech action by the gas before it is deposited upon either the firing chamber or the cartridge entering the firing chamber. The means for ejecting the lubricant into the gun is timed to operate at the proper instant in the cycle of operation, particularly in relation to the position of the cartridge in transit to the firing chamber and to the flow of gas from the mouth of the firing chamber, and this is

preferably effected by actuating the ejector by or with the breech closure.

In order to illustrate the nature of the invention a specific embodiment thereof is illustrated in the accompanying drawings in which,—

Figure 1 is a side elevation of the central part of a gun having the invention applied thereto, portions of the gun being shown in vertical longitudinal section and the receiver being broken away to show the breech action in elevation;

Fig. 2 is a horizontal longitudinal section on line 2—2 of Fig. 1;

Fig. 3 is a vertical transverse section on line 3—3 of Fig. 1;

Fig. 4 is an enlarged left side elevation of a part of the lubricating means; and

Fig. 5 is a vertical transverse section on line 5—5 of Fig. 4.

The gun illustrated in the drawings for the purpose of showing one concrete application of my invention is a semi-automatic army rifle comprising a stock H, a barrel A, a receiver R, a bolt B, an automatic bolt lock L, transmitters T, extractor E, ejector J, a bolt stop Y, a bolt stop spring N, a bolt stop washer W, recoil springs Q, a retractor r, a retractor pin t, a safety catch s, a trigger U, a trigger bar V, a tripper pawl X, etc. This rifle is fully described in my copending application Sr. No. 308,223 filed on even date herewith, and further description thereof is unnecessary for the purpose of the present application.

The lubricating means and the combination of the lubrication means with a gun, forming the subject-matter of the present invention will now be described.

The particular embodiment of my invention chosen for the purpose of illustration comprises in general a lubricant reservoir 1, a pump 2, a duct 3 leading from the reservoir to the pump, a duct 4 leading from the pump to the firing chamber, and a connector 5 connecting the duct 4 to the firing chamber.

The reservoir 1 is shaped as shown in Figs. 1 to 3 and is provided with flanges 6 and 7 adapted to slide behind flanges on the receiver as shown in Fig. 2 for the purpose of mounting the reservoir on the receiver, the reservoir sliding upwardly into the receiver when the stock is removed and being held in position by the stock or other suitable means. For the purpose of filling the reservoir from time to time a filling opening is provided in the bottom in alignment with the cartridge magazine opening in the stock so that the reservoir may be filled without removing the stock by inverting the gun, a plug 8 being provided to close this opening. The duct 3 and a part of the duct 4 are formed in the walls of the reservoir (Fig. 1), and a pump chamber is provided

in the rear end of the reservoir in communication with the ducts 3 and 4, the chamber being closed on the outside by a cover plate 20 extending throughout the length and depth of the reservoir and being soldered or welded or otherwise secured in place.

The connector 5 comprises a tubular member having a conoidal head adapted to seat in a conoidal recess in the bottom of the firing chamber and a base adapted to have the pipe 4 secured therein. The central portion of the connector has a smaller diameter and is surrounded by a coil compression spring 11 which bears against the under face of the head at its upper end and at its lower end bears against a washer 12 bifurcated to straddle the connector, the washer 12 sliding from the front into a guideway in the bottom of the forward end of the receiver and being retained in position by the stock 85 when the stock is attached to the gun. Thus the conoidal head of the connector is held tightly seated in the conoidal recess in the wall of the firing chamber by the spring 11. The passageway through the connector is 90 restricted at the upper end to a degree adapted to produce the desired pressure of the lubricant as it is delivered to the firing chamber; and the restricted passageway communicates with the opening in the wall 95 of the firing chamber which is inclined forwardly at the proper angle to eject the lubricant obliquely into the firing chamber, preferably in the form of a spray.

The lubricant pump comprises a pair of 100 spur gears 9 and 10 meshing together in the chamber in the rear end of the reservoir, which chamber is substantially no larger than is just sufficient to receive the gears. As shown in Fig. 1, the duct 3 leading from 105 the reservoir communicates with this chamber at the bottom, and the duct 4 leading to the firing chamber communicates with the chamber at the top. As the gears are rotated in the direction of the arrows (Fig. 1) lubricant is carried from the bottom to the top of the chamber in the spaces between the teeth and the end walls of the chamber, the gears fitting the chamber sufficiently snugly to prevent much if any lubricant from leaking back along the gears especially when the pump is acting against relatively low pressures. Oil is prevented from being carried from the top to the bottom of the chamber between the gears, at least in appreciable 110 measure, by the meshing teeth which substantially close the spaces between the teeth.

The pump actuating mechanism comprises a stud shaft 13, a ratchet wheel 14, a ratchet spring pawl 15, a ratchet arm 16, a ratchet 17 and a ratchet spring 18, as shown in Figs. 4 and 5. The stud shaft has two circular bearing portions journaled in the wall of the reservoir and the cover 20 respectively, a square portion fitting in a square 130

opening in the gear 9, a square portion fitting in a square opening in the ratchet wheel 14, a circular portion upon which the ratchet arm 16 is rotatably mounted, a 5 threaded end, and a smooth portion adjacent the threaded end, the cross-sectional size of the various portions being such that the stud shaft may be inserted from the right (Fig. 5). The threaded portion of the opening 10 in the ratchet arm 16 is substantially equal in length to the smooth portion of the stud shaft adjacent the threaded end thereof so that after being threaded on the stud shaft to the position shown in Fig. 5 the ratchet 15 arm is free to rotate on the stud shaft with substantially no lost-motion either axially or radially and can only be removed by oppositely rotating the two parts relatively to each other. In operation the relative rotation 20 is always in the same instead of the opposite direction, so that the ratchet arm is thus automatically prevented from becoming displaced from the stud shaft. The ratchet 17 has a lug 19 extending outwardly 25 through a slot in the side of the hollow ratchet arm into engagement with the ratchet wheel. The upper end of the hollow ratchet arm is closed by a plug 21 fast therein. A light spring 22 is provided to hold the 30 ratchet in contact with a tooth of the ratchet wheel except when the ratchet is forced in a clockwise direction (Fig. 4) as will hereinafter be described.

According to the present invention, in 35 one of its aspects, the lubricant pump is arranged to be actuated by some moving part of the breech action during the opening or closing of the breech action to deliver lubricant to the firing chamber (or to other desired 40 part or parts of the gun) each time the gun is fired or loaded, and as illustrated in the drawings the ratchet arm 16 projects upwardly into the path of a lug 23 on the right-hand side of the bolt and also in the 45 path of the rear face 24 (Fig. 1) of the lock L. As the bolt is advanced by recoil springs Q the lug engages the rear side of the ratchet arm and sharply rotates the arm to advance the ratchet wheel one notch, the 50 spring pawl 15 holding the ratchet wheel in advanced position against the back pressure of the lubricant. The lug 23 then passes over the ratchet arm, the arm being held down out of the path of the lug upon 55 the recoil of the bolt by means of spring 22. When the bolt automatically recoils, or is manually retracted, the face 24 of lock L engages the forward side of the ratchet arm to return it to upright position, thereby 60 bringing the ratchet 19 into engagement with the next ratchet tooth. The face 24 engages the ratchet arm on the recoil owing to the fact that this face extends lower than the lug 23 and the arm is left in upright 65 position owing to the fact that when the

bolt is completely retracted the face 24 of the lock stops in the plane of the forward side of the arm when in upright position.

Thus each time the bolt is plunged forward by the recoil springs the pump is 70 sharply actuated to produce a brief but sharp pressure on the head of lubricant between the pump and the firing chamber. If the orifice and pump are properly designed this pressure will cause a small amount of 75 oil to be sprayed into the firing chamber. By locating the actuating portion of the pump and the actuating portion of the breech action (the lug 23 in the illustrated example) in the proper positions the lubricant may be ejected at any desired instant 80 in the cyclic operation of the breech action, and as illustrated the lubricant is ejected at the time the cartridge is entering the firing chamber so that the cartridge passes through 85 the spray of lubricant and is coated thereby.

From the foregoing it will be evident that in its more specific aspect, the invention also involves the following characteristics: the pump arm 16 is inoperative when in its forward position inasmuch as it is out of the path of the actuating shoulder of bolt lug 23 and is restored to its operative position by the actuating shoulder 24 of lock L in the rearward movement of the bolt, thereby 95 avoiding a mechanical connection with the bolt.

What I claim is:

1. A gun comprising a firing chamber, an automatic breech closure, means for automatically feeding ammunition to said chamber, a lubricant reservoir, a duct extending from said reservoir to the mouth of said chamber, and means actuated by the breech closure in its closing movement to force 100 lubricant through said duct, said automatic breech closure and ammunition feeding means and lubricant forcing means being synchronized to spray lubricant on the ammunition in transit to the firing chamber. 105

2. A gun comprising a breech closure, means for lubricating parts of the gun each time the breech closure is actuated, said means having an operative and an inoperative position, and mechanism for actuating 115 said means during one movement of the closure, leaving the means in inoperative position, and then returning the means to operative position during the opposite movement of the closure.

3. A gun comprising a breech closure, means for lubricating parts of the gun, said means having an actuating part adapted to be moved into and out of operative relationship to said closure, and means for automatically moving said part into said operative position during one movement of the breech closure so that the means may be actuated during the opposite movement of the closure.

4. A gun comprising a breech closure, means for lubricating parts of the gun, said means including a gear pump and ratchet mechanism for actuating the pump, and
- 5 means for automatically advancing said ratchet mechanism during one movement of the closure and retracting the mechanism during the opposite movement of the bolt.
- 10 5. A gun comprising a breech closure, means for lubricating parts of the gun including a gear pump, ratchet mechanism for

actuating said pump, said mechanism having an arm adapted to actuate the pump when moved in one direction and to move independently of the pump in the opposite ¹⁵ direction, and said closure having shoulders respectively arranged to move said arm in opposite direction during the opening and closing movement of the closure.

Signed by me at Cleveland, Ohio this 20 twenty-fourth day of June 1919.

OLIVER B. GRAHAM.
